UNITED STATES PATENT OFFICE.

EMIL HUGO ADOLPH HAUPT, OF DOLGEVILLE, NEW YORK.

CAR-COUPING.

SPECIFICATION forming part of Letters Patent No. 298,577, dated May 13, 1884.

Application filed October 18, 1883. (No model.)

To all whom it may concern:

Be it known that I, EMIL HUGO ADOLPH HAUPT, a citizen of the German Empire, residing at Dolgeville, in the county of Herkimer and State of New York, have invented 5 new and useful Improvements in Car-Couplings, of which the following is a specification.

This invention relates, especially, to automatic couplings; and it consists in the novel 10 construction and arrangement of parts hereinafter described, whereby such couplings are automatically locked not only in a closed position, but also in an opened position, to be released, when desirable, by simply depressing 15 a certain part of the device.

In the accompanying drawings, Figure 1 shows a coupling, partly in top view and partly in horizontal section, embodying my invention. Fig. 2 is an inverted plan view thereof. 20 Fig. 3 is a horizontal section showing the parts in a different position from that shown in Fig. 1. Fig. 4 is a plan view showing the parts in a corresponding position to Fig. 1. Fig. 5 is a longitudinal section on the line $x-x$, Fig. 4. 25 Fig. 6 is a cross-section on the line $y-y$, Fig. 2. Fig. 7 is a like section on the line $z-z$, Fig. 4.

Similar letters indicate corresponding parts.

The letter A designates a draw-head constructed with a pocket, B, at or near one end, 30 to open in an upward direction, this pocket being closed under normal conditions by a cap-plate, C, which is fastened to the proper part of the head.

In the pocket B is arranged a rack-bar, D, between stops D' D'' , which also act as guides for the bar, and which are at such distances apart from each other as to allow the bar a slight longitudinal motion.

To one end of the rack-bar D is connected 40 a return-spring, a, which acts thereon with a tendency to draw it in the direction of the stop D' , so that under normal conditions the bar abuts against this stop under the impulse of the spring.

Into the teeth of the rack-bar D meshes a rotating pinion, E, which is arranged in a lateral projection, G' , of the bolt or coupling-pin G on an axial spindle, b, which extends upward 45 through a slot, d, in the cap-plate C, and is squared at the upper end to receive a key for

turning it. The bolt G is fitted into a guide-groove, e, of the pocket B, to slide therein, and is subjected to the action of a spring, f, having a tendency to force the same, in the direction of the arrow shown in Fig. 3, from the position shown in that figure, which is its rear or opened position, to that shown in Fig. 1, which is its closed position.

In the bottom of the pocket B are arranged 60 two bits or catches, H H', which are beveled in opposite directions and serve to lock the bolt G in its opened and closed positions, respectively, as hereinafter explained. Each of the catches H H' is pivoted, by means of its 65 shank, to move in a substantially vertical plane, and is subjected to the action of a spring, g or g', (best seen in Fig. 2,) having a tendency to force it to an upper or normal position—namely, through and above the level of the 70 bottom of the pocket B into the path of the projection G' of the bolt.

Levers I I' serve to retract the catches H H' against the action of the springs g g' in the following manner: The lever I oscillates in a 75 horizontal plane on a pivot-screw, i, and engages a notch, s, of the catch H at one end, while it is connected to the rack-bar D at the other end through a slot, o, in the bottom of the pocket B in such a manner that when the 80 rack-bar is displaced against its return-spring a it acts on the lever I to throw the proper end thereof out of said notch of the catch onto a plain portion of the latter, as indicated in Fig. 5, whereby the catch is forced in or 85 downward. The lever I' oscillates in a vertical plane on a pivot-shaft, k, and engages a notch of the catch H' at one end, it being fixed to the shaft, together with a second lever, J, to which is connected a vertical push-bar, J', 90 in such a manner that when this bar is depressed the lever I' shares its motion and displaces the catch. The push-rod I extends upward through the cap-plate C, and is provided at the upper end with a head or button, 95 l, whereby it may be conveniently depressed by the foot. Protection is afforded to the catches H H' and concomitant parts by arranging the same in a recess, M, formed at the proper place in the draw-head A, such 100 recess being provided with a suitable cover.

Adjacent to the pocket B, in an inward di-

rection, the draw-head A is provided with a mouth, N, to receive the coupling-link O of another draw-head. In this mouth is arranged a projection, P', of a tumbler, P, which works in a pocket, Q, of the draw-head, and is subjected to the action of a spring, Q', having a tendency to force the same in an outward direction. The tumbler P has a second projection, P², which is arranged in a branch, o Q², of the pocket Q, to intersect a channel or passage G², which receives the bolt, such channel being continued from one to the other side of the mouth or link-receptacle N of the draw-head. When the bolt G is in a closed position, as shown in Fig. 1, the catch H engages the projection G' thereof, and thus locks the bolt in the position named. When it is desired to retract the bolt, the pinion E is turned in the direction of the arrow shown in Fig. 1 o by means of a key fitted to the spindle b, as before stated, and in the initial movement of the pinion the rack-bar D is thereby displaced against the action of its spring a to the extent allowed by the stop D", as indicated in Fig. 5 4, while during the movement of the bar it acts on the lever I to cause the retraction of the catch H, as before explained, so that the bolt is permitted to pass over the catch. As the motion of the pinion E is continued, the bolt travels inward, and its projection G' comes in contact with and rides over the catch H', the bevel of this catch being proper for this purpose, while when the projection has cleared the catch the latter engages therewith, as shown in Fig. 3, thus locking the bolt in what constitutes its opened position. To release the bolt the push-bar J' is depressed to cause the retraction of the catch H', whereby the bolt is set free and allowed to follow the action of its spring f, under the impulse of which the leading end thereof is brought in contact with the projection P' of the tumbler. If the link O is then introduced into the mouth N of the draw-head, the tumbler P is forced back against the action of its spring by the contact of the link with the tumbler-projection P', and inasmuch as the projection P² is likewise displaced it clears the path of the bolt, so that the latter may enter the link, the catch H at the same time re-engaging the bolt, so that it becomes locked. In the motions of the bolt G the spindle b travels in the slot d of the cap-plate, and when the bolt has reached either extreme position this slot may be closed 55 by a suitable cover.

In applying the coupling to use the adjacent ends of two cars are each provided with a draw-head A similar to the other, the link O of one head being arranged opposite to the mouth N of the other head, as shown in Fig. 1. Said link O is pivoted at the inner end to

a slide, R, which is arranged in a pocket, R', of the draw-head, and is exposed to the action of a spring, R², having a tendency to force it inward, so that the spring tends to counteract 65 the draft on the link, while the latter is left free to perform the required lateral movements.

In the center of the draw-head is arranged a buffer, S, of any usual or suitable construction.

What I claim as new, and desire to secure by Letters Patent, is—

1. The combination of the draw-head having the pocket B, the rack-bar D, arranged 75 between stops in said pocket, the return-spring of the rack-bar, the spring-impelled bolt having the lateral projection G', the pinion E, arranged in said projection of the bolt to engage the rack-bar, the axial spindle of 80 the pinion, the bolt-catches C C', and means, substantially such as hereinbefore described, for retracting said catches.

2. The combination of the draw-head having the pocket B, the rack-bar D, arranged 85 between stops in said pocket, the return-spring of the rack-bar, the spring-impelled bolt having the lateral projection G', the pinion E, arranged in said projection of the bolt to engage the rack-bar, the axial spindle of 90 the pinion, the catches C C', the retracting-lever I, engaging the catch C and connecting with the rack-bar, the retracting-lever I', engaging the catch C', and the push-bar J', acting on the lever last mentioned. 95

3. The combination of the draw-head having the pockets B Q, the mouth or link-receptacle N, and the bolt-passage G², the rack-bar D, arranged between stops in the pocket B, the return-spring of the rack-bar, the spring-100 impelled bolt having the lateral projection G', the pinion E, arranged in said projection of the bolt to engage the rack-bar, the axial spindle of the pinion, the catches C C', means, substantially as herein described, for retracting 105 the catches, and the tumbler P, working in the pocket Q, and having projections P' P²—one arranged in the link-receptacle, and the other arranged to intersect the bolt-passage.

4. The combination, with the draw-head 110 having the mouth or link-receptacle N, and coupling mechanism, substantially such as herein described, of the slide R, the spring acting on the slide, and the link pivoted to the slide at the inner end. 115

In testimony whereof I have hereunto set my hand in the presence of two subscribing witnesses.
